UNITED STATES PATENT OFFICE

133,554

DESIGN FOR A BANNER OR SIMILAR ARTICLE

Fred J. Ullrich and Franklin E. Quale,
Kalamazoo, Mich.

Application April 28, 1942, Serial No. 106,735

Term of patent 3½ years

To all whom it may concern:

Be it known that we, Fred J. Ullrich and Franklin E. Quale, residing at Kalamazoo, in the county of Kalamazoo and State of Michigan, respectively, have invented a new, original, and ornamental Design for a Banner or Similar Article, of which the following is a specification, reference being had to the accompanying drawing, forming part thereof.

The figure is an elevational view of a banner or similar article, showing our new design.

We claim:

The ornamental design for a banner or similar article, as shown.

FRED J. ULLRICH.
FRANKLIN E. QUALE.
